ABSTRACT

A remote control switch circuit for switching on and off an associated load with a remote control relay operated by one of a plurality of remote control switches which is actuated independently of others. The circuit comprises a series circuit of a remote load section including the remote control relay connected to the load and normally closed and normally opened contacts connected in series through a pair of reversely connected diodes to the relay and a first operating switch section including the remote control switch for initiating and interrupting current fed to a polar relay and normally closed and normally opened contacts connected in series through a pair of reversely connected diodes to the switch, and an AC source providing source voltage to said series circuit. Other operating switch section or sections will be connected to said first section in parallel relation thereto.

REMOTE CONTROL SWITCH CIRCUIT

This invention relates to a remote control switch circuit wherein a remote control relay is independently operated by either one of remote control switches provided in several places to switch on and off a load.

Conventional remote control switches of this kind have defects that they are of a very complicated formation, that, when the remote control relay circuits increase, the wirings will be complicated and that, when the number of indicating lamps increases, the life of the auxiliary contact of the remote control relay will reduce since the lamp current will flow through the auxiliary contact. The present invention has been suggested to remove these defects.

Principal object of the present invention is to provide a remote control switch circuit wherein loads can be steppedly remote-controlled by a simple combination of circuit elements.

Another object of the present invention is to provide a remote control switch circuit wherein, even if the number of indicating lamps increases, the life of the auxiliary contact of the relay will not be reduced.

A further object of the present invention is to provide a remote control switch circuit wherein the wiring can be simplified.

The present invention shall be explained in the following with reference to accompanying drawings, in which:

FIG. 1 shows an embodiment of the remote control switch circuit of the present invention.

FIGS. 2A-2G are time charts for explaining the operation of the circuit of FIG. 1.

FIG. 3 is a block diagram showing a wiring of a plurality of the circuitry systems in FIG. 1.

FIG. 4 shows a further improved embodiment of the remote control switch circuit of the present invention.

FIGS. 5A-5G are time charts for explaining the operation of the circuit of FIG. 4.

FIG. 6 is a block diagram showing a wiring relation in the case of wiring a plurality of the circuitry systems in FIG. 4.

In FIG. 1 showing a remote control switch circuit of the present invention, A_c is an alternating current source, A_1 is a remote control relay circuit, that is, a remote load section and B_1 to B_3 remote control switch sections or operating switch sections. Referring further to the formation of the remote control relay circuit A_1 , R_y is a first polar relay coil, r_1 and r_2 are contacts to be set ON and OFF by the operation of the relay coil R_y , D and D' are diodes and r_a , r_b and r_c are contacts forming the contact r_1 . Referring next to the formations of remote control switch section B_1 , S_1 is a change-over switch, S_{1a} and S_{1b} are contacts, $R1_1$ is a second polar relay for making a switching operation depending on the direction of the current, $R1_1'$ is its contact, $1a$ and $1b$ are contacts, D_1 and D_1' are diodes and L_1 is an indicating lamp. The polar relay $R1_1$ in the present instance is so formed that, when the current flows in the direction indicated by the arrow a , the contact $1a$ will close and, when the current flows in the direction indicated by the arrow b , the contact $1b$ will close. The formations of the respective sections B_2 and B_3 are also the same as of the section B_1 .

In this circuit, when any of the remote control switch sections B_1 to B_3 is operated, the remote control relay

R_y will be controlled and the contact r_2 will be set ON or OFF so that the load will be switched on or switched off.

Now, the operation of the circuit of the present invention shall be explained in detail. In the state shown in FIG. 1, the remote control relay R_y is not in operation.

If, for example, the switch S_1 is operated so that the contact S_{1a} will be ON and S_{1b} will be OFF (see FIG. 10 2A), a closed circuit of $A_c \rightarrow r_c \rightarrow r_b \rightarrow D' \rightarrow R_y \rightarrow S_{1a} \rightarrow 1b \rightarrow D_1 \rightarrow A_c$ will be formed and the contact r_2 of the relay R_y will be set ON (see FIG. 2G). Then, if the remote control relay R_y operates, the contact r_1 will be switched so that r_a will be ON and r_b will be OFF (see FIG. 2C) and a current will flow through the diodes D_1' and D to light the indicating lamp L_1 .

Next, if the switch S_1 is operated so that the contact S_{1a} will be OFF and S_{1b} will be ON, a current will flow through a closed circuit of $A_c \rightarrow R1_1 \rightarrow S_{1b} \rightarrow R_y \rightarrow D \rightarrow r_a \rightarrow r_c \rightarrow A_c$ from the current source A_c and, as the direction of this current is the direction indicated by the arrow a , the contact of the relay $R1_1$ will be switched so that the contact $1a$ will be ON and $1b$ will be OFF (see FIG. 2D). Thus the next operation is prepared.

Then, if the switch S_1 is operated so that the contact S_{1a} side will be again ON, a current will flow through a circuit of $A_c \rightarrow D_1' \rightarrow 1a \rightarrow S_{1a} \rightarrow R_y \rightarrow D \rightarrow r_a \rightarrow r_c \rightarrow A_c$ from the current source A_c , the remote control relay R_y will reverse as in FIG. 2B, the contact r_a will be OFF, r_b will be ON, no current will flow through the remote control relay R_y and thus no current will flow through the indicating lamp L_1 which will go out as shown in FIG. 2F. Then, if the switch S_1 is operated so that the contact S_{1b} side will be ON, a current in the direction indicated by the arrow b will flow through the polar relay $R1_1$ and the contact of the polar relay $R1_1$ will be switched over to the b side.

Such operations as in the above are made. In this system, as the current indicating lamps L_1 to L_3 are respectively connected in series with the remote control relay R_y , if many indicating lamps are connected, a large current will flow through the remote control relay R_y and errors will be likely to be caused. Therefore, it is necessary that only such number not interfering with the operation of the remote control relay R_y as, for example, two lamps L_1 and L_2 of the remote control switch sections B_1 and B_2 should be connected in series but the third lamp L_3 should be connected so as not to be in series with the remote control relay R_y . Therefore, the lamp L_3 is connected with the connecting point of the contact r_a of the remote control relay R_y and the diode D by using a lead wire 1. However, there are defects that, for example, as shown in FIG. 3, in the case of the three circuits of the remote control relays A_1 to A_3 , the number of wirings will increase by the number of the remote control relay circuits, therefore, the connection of the third switch section B_3 will be complicated, the current flowing through the lamp will flow to the auxiliary contact of the remote control relay R_y and therefor the life of the auxiliary contact will reduce. The circuit system in FIG. 4 has been suggested to improve these defects.

In FIG. 4 showing a further improved embodiment of the present invention, A_1 is a remote control circuit, and B_1 to B_3 are operating switch sections. The relay

Ry, polar relays R1₁ to R1₃, switches S₁ to S₃, lamps L₁ to L₃, diodes and relay contacts used to form A₁ and B₁ to B₃ are represented respectively by the same corresponding numerals as in FIG. 1. The feature of this circuit system is that the diodes D₄ to D₆ are connected in series with the lamps L₁ to L₃. The diodes D₄ and D₅ are connected between such number not interfering with the operation of the remote control relay Ry as, for example, two lamps L₁ and L₂ of the remote control switch sections B₁ and B₂ and contacts 1c and 2c (movable contacts of the polar relays R1₁ and R1₂) and the lamp L₃ of the rest remote control switch section B₃ is connected through the diode D₆ between the movable contact r_c side (one end of the current source Ac) of the switching auxiliary contact r₁ of the remote control relay Ry and the movable contact 3c of the switching contact R1₃' of the polar relay R1₃. The other formation is the same as in the case of FIG. 1 and the operation is also exactly the same as in FIG. 1. FIG. 5 shows a time chart of the present invention.

In the present invention, as described above, as the current of the indicating lamps flowing through the auxiliary contact of the remote control relay Ry is not larger than for two lamps, even if the number of lamps increases, the life of the auxiliary contact will not be reduced. Further, as shown in FIG. 6, as the electric wire corresponding to 1 in FIG. 3 can be made only a single electric wire 1a, the third switch section B₃ will be also of the same number of wirings as of the first and second switch sections B₁ and B₂ and the wirings can be simplified.

What I claim is:

1. A remote control switch circuit comprising the combination of
  - a remote load section comprising
    1. a first polarized relay coil for operating the contacts of a load,
    2. a pair of oppositely facing diodes connected in

parallel with each other with one end of the parallel diodes connected to said coil,

3. and a switch operated by said first polarized relay coil and connected to the other end of the parallel diodes for connecting alternate ones of said diodes in series with said coil in response to energization of said coil by signals of alternate polarities,
- b. and at least one operating switch section comprising
  1. a second polarized relay coil,
  2. a second pair of oppositely facing diodes connected in parallel with each other and with said second coil,
  3. a manually operated switch connected in series with said first polarized relay coil for connecting either said second coil or the second pair of diodes in series with said first coil,
  4. a switch operated by said second polarized relay coil connected between said manually operated switch and said second pair of diodes for connecting alternate ones of said second pair of diodes in series with said manually operated switch in response to energization of said second coil by signals of alternate polarities,
  5. and an indicating lamp connected in series with said first polarized relay coil and at least one of the diodes in said second pair.
- c. and an a-c source connected across said remote load section and said operating switch section.
2. A remote control switch circuit as set forth in claim 1 which includes a plurality of said operating switch sections in at least one of which the indicating lamp is connected in series with at least one of the diodes in said second pair and said a-c. source, and including a further diode connected in series with said indicating lamp.
